AIR DISTRIBUTING UNITS

William C. Jones, Medford, Mass., assignor to Westinghouse Electric Corporation, East Pittsburgh, Pa., a corporation of Pennsylvania

Application October 1, 1951, Serial No. 249,085

3 Claims. (Cl. 98—38)

This invention relates to air distributing units such as are used in air conditioning systems for supplying heated air or chilled air or a mixture of heated and chilled air as required, at local distributing points.

Air distributing units embodying this invention are for use in individual rooms or other remote locations, for receiving heated and chilled air supplied through separate ducts from a central air conditioner. Each unit operates to supply chilled air only, heated air only, or a mixture of heated and chilled air, as required for maintaining a desired temperature within the space served by the unit.

A feature of this invention is that a plenum chamber is provided at one end of a unit for the reception of heated air, another plenum chamber is provided at the other end of the unit for the reception of chilled air, the inner ends of the plenum chambers being spaced apart and provided with aligned air outlet openings, and interconnected dampers are movable in the space between the plenum chambers for simultaneously opening one of the outlet openings and closing the other of the outlet openings, the dampers being designed to provide a constant volume of air through the unit for every position of their settings.

Another feature of this invention is the provision of an elongated air mixing chamber above the two plenum chambers and the space therebetween, and the provision of a labyrinth of sound absorbing material in the mixing chamber for absorbing sound in the air flowing to an upper discharge outlet, and for offering resistance to the air flow for reducing its velocity.

An object of this invention is to provide proper mixing of two streams of air having different temperatures for supply at a constant volume into a conditioned space.

Another object of the invention is to reduce noise in the air discharged from an air distributing unit.

The invention will now be described with reference to the drawings, of which:

Fig. 1 is a side elevation, partially in section, of an air distributing unit embodying this invention, and

Fig. 2 is an end elevation, partially in section, of the unit.

The unit illustrated comprises a relatively long, relatively tall and relatively narrow sheet metal casing 10 having an inlet 11 for heated air in one end of its lower portion, and having an inlet 12 for chilled air in the opposite end of its lower portion. The inlets 11 and 12 are adapted to be connected to ducts which convey heated and chilled air from a central conditioner which may be located in the basement or on the roof of a building.

The unit has a relatively long and relatively narrow slot 13 in its upper wall forming an air discharge outlet, and has the adjustable vanes 14 below the slot for adjusting the velocity and volume of the air discharge from the unit.

The unit when installed in a room of a building, would have the enclosure 16 of sound insulating material therearound, and which would have the air outlet 17 above the slot 13.

2

The air inlet 12 discharges into the plenum chamber 18 which has an air outlet 19. The air inlet 11 discharges into the plenum chamber 20 which has the air outlet 21. The plenum chambers 18 and 20 are at the opposite ends of the unit, and their air outlets 19 and 21 respectively, are in horizontal alignment and are spaced apart.

The parabolic dampers 22 and 23 are located within the space between the outlets 19 and 21. The damper 22 is attached to the inner end of the rod 24 which extends through the sleeve 25. The sleeve 25 is attached to the damper 23. The rod 24 is attached to the sleeve 25 through the nut 33 which is threaded on the rod being brazed to the outer end of the sleeve. The outer end of the rod 24 is attached to the inner end of the pivoted lever 26, the outer end of which is attached to the lever 27 which is pivoted at 28 to the U-shaped member 29. The lever 27 is also attached to the threaded rod which is pivoted to the threaded portion 31 of the air cylinder 32 which is connected to a compressed air line 42 under control of the room thermostat T which varies the volume of compressed air bled from the bleed port 43 in the line 42. The air cylinder 32 is a conventional "Pneumatic Damper Motor" such as is manufactured by the Johnson Service Co. which may also manufacture the thermostat 25 T and the line 42 with the bleed port 43. The cylinder 32 contains a piston which is not shown, which is moved downwardly by air pressure against the resistance of a coiled spring which is not shown. The line 42 is connected to a conventional source of compressed air which is not shown.

Upon an increase in room temperature, the thermostat T will move nearer the bleed port 43, decreasing the volume of air bled therethrough. This will cause an increase in the air pressure against the piston in the cylinder 32, causing the piston to be moved downwardly, moving the upper end of the lever 27 downwardly, causing the lower end of the lever to move outwardly and upwardly. This will cause the rod 24 and sleeve 25 to which the dampers 22 and 23 respectively, are attached, to move outwardly, causing the hot air damper 23 to move towards closed position, and the cold air damper 22 to move towards open position.

The positions of the dampers thus depend upon the volume of air bled from the bleed port 43, which volume, in turn, depends upon the position of the thermostat relative the bleed port. A reduction in room temperature will cause the thermostat to move away from the bleed port permitting more air to be bled therefrom and causing a reduction in the air pressure against the piston in the cylinder 32. The spring in the cylinder will move the piston upwardly, causing the rod 24 and sleeve 25 to move inwardly so as to cause the hot air damper 23 to move towards open position and the cold air damper 22 to move towards closed position.

The nut 33 which is threaded on the rod 24 adjacent the outer end of the sleeve 25 can be adjusted for varying the position of the damper 22 relative the damper 23. By backing off the locknut 44 and screwing the nut 33 forwardly on the threaded rod 24, the sleeve 25 can be moved inwardly so as to move the damper 23 nearer the damper 22. By backing off the nut 33, the damper 23 can be moved away from the damper 22. The movement of the two dampers as a unit can be adjusted by connecting the outer end of the lever 26 to the one of the pivot points 35 which suits, and by adjusting the nuts 36 and 37 on the rods 31 and 30 respectively.

The rod 24 is supported between the dampers 22 and 23 by the bearing 38 which is attached to the angle 39 the ends of which are secured to opposite sides of the unit.

The dampers 22 and 23 and their associated outlets 19 and 21 respectively, are so designed that as one outlet is closed, the other is opened the same amount so that the

total volume of air passed through the unit is always constant, this assuring that there is a uniform increase in the air from one outlet and a uniform decrease in the air from the other outlet as the control cylinder is modulated.

The boards 40 of conventional sound insulating material are attached to the ends of the unit and form a labyrinth passage through which the air passing the dampers 22 and 23 moves in a zig-zag path. This causes the sound in the air to be absorbed and the velocity of the air to be reduced.

In operation, the high velocity air under substantial pressure from a central conditioner is supplied into the plenum chambers 18 and 20 where it expands and has its velocity reduced. The room thermostat T would determine whether or not heated air or chilled air or a mixture of the two would be supplied by the unit. The air passing the dampers expands further into the space occupied by the sound absorbing boards 40 where it has its velocity further reduced both by expansion and by the resistance offered by the tortuous passage through the sound absorber. The air is then discharged into the room through the outlet 17 with substantially less velocity and sound content than when it entered the unit.

In winter, one of the air streams would be heated and the other unheated or heated sufficiently to avoid freezing temperatures.

In summer, one of the air streams would be chilled by refrigeration, and the other would normally be outdoor air untreated except possibly by cleaning.

However, during border-line months at the beginning of summer and the end of summer, rooms at the shaded side of a building may require heating while those at the sunny side of the building may require cooling at the same time so that at times heated and chilled air may simultaneously be supplied to the air distributing units of such a building.

While one embodiment of the invention has been described for the purpose of illustration, it should be understood that the invention is not limited to the exact apparatus and arrangement of apparatus illustrated since modifications thereof may be suggested by those skilled in the art without departure from the essence of the invention.

What I claim as my invention, is:

1. An air distributing unit comprising a relatively long and relatively narrow casing, means including the bottom and one end of said casing forming a relatively large cold air plenum chamber extending a substantial distance into said casing, means including the bottom and the opposite end of said casing forming a relatively large warm air plenum chamber extending a substantial distance into said casing, said chambers having relatively small air inlets and having spaced apart inner walls having aligned, relatively small air outlets having a common axis therein, a pair of dampers movable within the space between said inner walls for opening and closing said outlets, said casing having a warm and cool air mixing chamber extending the length and width thereof above said plenum chambers, and having an air outlet above said mixing chamber, and means including means interconnecting said dampers for simultaneously moving said dampers along said axis.
2. An air distributing unit as claimed in claim 1 in which the means for moving the dampers includes a rod connected to one of the dampers and extending through one of said chambers and one of the end walls of said casing, and a sleeve connected to the other damper and extending around and attached to the rod.
3. An air distributing unit as claimed in claim 2 in which means is provided for adjusting the position of said sleeve along said rod for varying the spacing between said dampers.
